UNITED STATES PATENT OFFICE.

ALFRED ALSAKER AND SIDNEY J. LURIE, OF CHICAGO, ILLINOIS, ASSIGNORS TO THE DELTA-STAR ELECTRIC COMPANY, OF CHICAGO, ILLINOIS, A CORPORATION OF ILLINOIS.

SWITCH.

Application filed September 2, 1927. Serial No. 217,036.

Our invention relates, in general, to electrical switching devices, and more particularly to such switching devices as are known in the art by the term "disconnect switches".
 5 As is well known, disconnect switches are usually placed in series with circuit breakers and such apparatus, and are used to isolate the switches and apparatus with which they may be associated, so that they may be worked upon with safety. Obviously, switches of
 10 this character may not be operated for long periods of time and are frequently very difficult to operate. In addition, such switches are used a great deal in outdoor substation equipment where they are likely to become
 15 coated with ice and sleet in the winter months, thus rendering them very difficult to operate. In view of the foregoing, it becomes necessary to provide means whereby the disconnecting switches may be readily operated even under the most adverse conditions.

One of the objects of our invention is to provide means for imparting an initial or preliminary movement to the switch blade
 25 of the disconnect switch of relatively greater force than would be applied by the simple opening movement, to overcome any bind or lock between the switch blade and the stationary terminal, whether it is due to ice or sleet, or static friction.
 30

Another object is to provide a disconnect switch in which the switch blade may be mounted so that the movement to open the switch may occur in either a clockwise or
 35 counterclockwise direction without any material alteration of the switch structure.

Another object is to provide a disconnect switch of the above type in which the switch blade, in addition to having the preliminary
 40 or ice breaking movement when the switch is opened, has a similar movement when the switch is closed.

Another object is to provide an improved mounting for a disconnect switch of the character described for so counterbalancing it that it may be more easily operated.

There are other objects of our invention which, together with the foregoing, will be described more in detail in the specification which is to follow, taken in conjunction with the accompanying drawings.

In its preferred form, our invention consists essentially of two insulator stacks mounted upon a base by offset brackets, one

of these insulators being rotatably mounted 55 and having affixed thereto a suitable blade mechanism by a second offset bracket. The other insulator stack carries the usual stationary terminal mounted thereon by an offset bracket so as to be in alignment with 60 the switch blade. The blade mechanism is so constructed that when the insulator is rotated, a preliminary longitudinal movement of great force is applied to the blade to break whatever bind there may be between 65 the blade and the terminal, either by reason of static friction, corrosion, ice or sleet. The subsequent rotation of the blade in its opening movement occurs in the usual manner.

Referring now to the drawings, 70

Fig. 1 is a side elevation of our improved switch;

Fig. 2 is a top plan view of the disconnect switch;

Fig. 3 is a fragmentary section along the 75 line 3—3 of Fig. 2, looking in the direction of the arrows showing detail of the stationary terminal or contact member;

Fig. 4 is a detail section along the line 4—4 of Fig. 2, looking in the direction of the arrows; 80

Fig. 5 is a detail section along the line 5—5 of Fig. 2 looking in the direction of the arrows, showing a view of the contact, together with the switch blade in its closed position; 85

Fig. 6 is an enlarged longitudinal section of the switch blade along the line 6—6 of Fig. 2, showing the mechanism involved in the so-called "A. R. T." movement which is employed to break any bind between the blade 90 and the terminal;

Fig. 7 is a cross section of the switch blade along the line 7—7 of Fig. 6;

Fig. 8 is a cross section along the line 8—8 of Fig. 6, showing the manner in which the 95 rotary insulator bracket is affixed to the switch blade mechanism;

Fig. 9 is a cross section along the line 9—9 of Fig. 6, showing the manner in which the base bar and the switch blade are pivotally 100 fastened together;

Fig. 10 is a top plan view of the switch blade when the disconnect switch is partially open, showing various constructional details; and

Fig. 11 is another top plan view of the switch blade mechanism on an enlarged scale showing a modification of the invention wherein

the so-called "A. R. T." movement is imparted to the switch blade, both upon opening and closing the switch.

Referring now to the drawings in detail, in which like reference characters in the various figures designate similar parts, reference characters 1 and 2 designate a pair of stack insulators of any usual construction mounted by means of the offset brackets 3 and 4 upon a channel base 5. The support 5 is U-like in shape and is grounded in any suitable or desired manner. The offset bracket 4 is mounted upon a rotary bearing 6 attached to the channel base 5. The rotary bearing 6 is of the construction illustrated and described in the co-pending application of Alfred Alsaker, Ser. No. 137,926, filed September 27, 1926. The bearing 6 is adapted to be rotated by the link member 7 through the medium of a pipe 8 that is operated in the usual manner by a switch handle (not shown). A spring 9 is adapted to be tensioned when the insulator 6 is rotated, since it is attached to the pipe 8 by the clevis 10. The spring 9 is provided for the purpose of balancing the switch blade to render the operation of the latter very easy. The switch blade mechanism 10 is attached to the rotary insulator stack 2 by means of the offset bracket 11. The switch blade mechanism 10 is attached to the offset bracket 11 by means of the bolt 12 passing through the blade base 13. Pins 14 and 15 are provided to prevent the rotation of the blade base on the offset bracket. The blade base 13 is attached at one end to the switch blade 16 by the bolt 17 which also constitutes a holding means for the terminal lug 18. The switch blade 16 is rotatably fastened by the bolt 17 which may be designated the terminal pivot. The terminal pivot 17 passes through a short longitudinal slot 35 in the switch blade 16. A flexible conductor 19 extends from the terminal 18 to the switch blade 16 to by-pass the terminal pivot 17, thereby providing a good electrical connection between the terminal and the switch blade. As may be seen from Fig. 1, the center of the pivot 17 passes through the center of the rotary bearing 6, hence it coincides with the axis about which the switch member rotates. As a result, there is no turning movement of the terminal member 18 during the rotation of the switch, the member 18 remaining in the same position whether the switch is open or closed. The terminal pivot 17 is protected from ice by the sleet shield 19'. A reenforcing member 20 of steel or other suitable material is attached to the switch blade in any well known or desired manner. The upper end of the switch blade is attached to the blade base by means of a link member 21. The link member 21 is pivotally fastened to the switch blade at 22 and pivotally fastened to the blade base at 23. Bracket 24 is attached to

the blade base and constitutes a holding means for a spring 25 which is attached to the switch blade by means of the bracket 26. This peculiar assembly of the switch blade mechanism constitutes a toggle and serves to impart the initial or preliminary longitudinal movement to the switch blade, as will appear.

The stationary insulator stack 1 carries an offset or adapter bracket 27 to which is attached the stationary terminal or contact member 28.

The detailed construction of the stationary terminal member may be seen by referring to Figs. 3, 4 and 5. The stationary terminal 28 is of the usual construction, being provided with two contact members 29 and 30 mounted on either side of the terminal lug 50 by the bolt 51, flared outwardly on the side adapted to be engaged by the switch blade and held resiliently by the leaf spring members 31 and 32. The terminal lug 50 carries the usual extension 52 that furnishes a stop for the switch blade.

Having described the mechanical construction of our improved disconnect switch, we will now explain the manner in which the various parts function.

When it is desired to open the switch, the rotary insulator is rotated in a clockwise direction. Since the rotary insulator 2 is fastened to the blade base, the blade base 13 is rotated. The blade base is fastened to the switch blade by the link 21 and, therefore, the movement of the blade base serves to move the switch blade 20 in a longitudinal direction, the switch blade 20 moving in the slot 35. This longitudinal movement is very much more powerful than any movement that could be imparted to the switch blade by merely rotating it. When the end of the slot 35 is reached by the movement of the blade 16 in a longitudinal direction, it is then rotated in the usual manner. The preliminary movement of the blade base serves to tension the spring 25. Now, when the rotary movement of the switch blade takes place, the spring 25 moves the switch blade so that the whole assembly takes its original or normal position, the switch blade 16 moving forward in the slot 35.

When the switch is closed by moving the rotatable insulator 2 in a contra-clockwise direction, the stop 36 attached to the blade base 13 engages the side of the switch blade 16 and the switch blade assembly 10 moves as a unit until the switch blade is forced into the stationary terminal.

When the switch blade 16 is rotated to open the switch, the spring 9 is tensioned to counterbalance some of the weight of the switch blade. The insulator stacks 1 and 2 are offset in the usual manner in order to protect their petticoats from moisture. The use of the offset brackets 3 and 4 and 11 and

27, permits standard type insulator stacks to be used without change in this offset assembly. Since the rotatable insulator stack 2 is attached to the blade base 13 at its upper end, 5 the weight of the switch blade is partially counterbalanced. The offset mounting of the insulator stacks 1 and 2 also provides that the only force applied to the insulator stacks is a cantilever one instead of a torsional one. 10 It will be seen that after this preliminary longitudinal movement is given the switch blade 16 and the rotary movement of the switch blade is begun, the spring 25 operates to force the switch blade back to its original 15 position with a snapping movement. Where very large switches are used having long and heavy switch blades of upwards of five feet in length, there is considerable vibration set up by this snapping movement. It therefore 20 is desirable to eliminate this snapping movement on the large switches. In order to accomplish this result with a minimum change in the switch structure, the mounting of the spring 25 was changed so that instead 25 of tending to force the blade base and the switch blade into alignment at the beginning of the rotary movement, it tended to hold them apart. This construction may be seen with reference to Fig. 11. In this figure the 30 spring 25 is attached to the switch blade by the bracket 40 which extends slightly beyond the edge of the switch blade. The other end of the spring is attached to the bracket 41 which is mounted upon the blade base 13. By 35 thus mounting the spring 25, it will be seen that the tendency of the spring is to maintain the switch blade assembly 10 in the position shown during its rotary movement.

The operation in this case is somewhat 40 different, since there is a double "A. R. T." movement of the switch blade, one on closing the switch and one upon opening the switch. It will be seen that when the rotary insulator 45 2 carrying the switch blade 13 is rotated under these conditions, the switch blade 16 rotates until the end of the blade engages the stop 52 carried by the stationary terminal assembly. Thereupon, since the switch blade can no longer be rotated, the toggle action, 50 including the blade base 13 and the link 21, is forced into alignment with the switch blade 16, whereby the switch blade is moved in a longitudinal direction into its closed position.

When the switch is opened, the blade base 55 is rotated to move the switch blade in a longitudinal direction until the end of the slot 35 is reached, after which a rotary movement of the switch blade occurs.

It sometimes becomes desirable in certain 60 installations to have the switch blades opened with a contra-clockwise movement instead of a clockwise movement, exactly the reverse from that herein described. It therefore becomes highly desirable to accomplish this 65 result without material change in the con-

struction of the switch. In our improved switch, all that is necessary to do to cause the switch blade to be rotated in a contra-clockwise direction to open the switch, is to reverse the stationary terminal and to mount 70 the stop 36 of the switch blade on the opposite side of the base blade 13. These changes will permit the type of disconnect switch shown in Figs. 1 to 10, inclusive, to operate in the desired manner. The toggle link comprising the blade base 13 and the link 21 simply move to the other side of the switch blade into a position corresponding to the one shown in the drawings when the switch is opened. 80

With the type of switch shown in Fig. 11, all the preceding changes must be made and, in addition, the bracket 40 carrying the spring 25 is mounted upon the other side or edge of the switch blade 16, while the bracket 85 41 on the blade base 13 may be left in its present condition. With these changes, the disconnect switch having the switch blade mechanism of the construction shown in Fig. 11, may be operated in a contra-clockwise direction to open the switch and in a clockwise 90 direction to close it.

We desire it to be understood that, although we have disclosed and described a preferred form of our invention, the invention is not limited thereby, but only in so far as defined by the scope and spirit of the appended claims. 95

We claim:—

1. A switch comprising a switch terminal, a 100 blade for contacting said terminal, a supporting member for said blade pivotally attached thereto at one end, and a link member connecting the other end of said supporting member to said blade. 105

2. A switch comprising a switch terminal, a blade for contacting said terminal, a supporting member for said blade pivotally attached thereto at one end through a slot in 110 said blade, and a link connecting the other end of said supporting member to said blade. 115

3. A switch comprising a switch terminal, a blade for contacting said terminal, a supporting member for said blade pivotally attached thereto at one end through a slot in 115 said blade, a link connecting the other end of said supporting member to said blade, and means for rotating said supporting member to cause said blade to move longitudinally in said slot. 120

4. A switch comprising an insulated support including an oscillatory insulator, a supporting member rigidly mounted upon said insulator, a switch blade pivotally connected to said supporting member at one end and a link member for connecting the other end of said supporting member to said switch blade. 125

5. A switch comprising an insulated support including an oscillatory insulator, a supporting member rigidly mounted upon said 130

insulator, a switch blade pivotally connected to said supporting member at one end, a link member for connecting the other end of said supporting member to said switch blade, and resilient means for maintaining said link member and said supporting member normally in alignment with said switch blade.

6. A switch comprising an insulated support including an oscillatory insulator, a supporting member rigidly attached to said insulator, a switch blade pivotally connected to one end of said supporting member, a link member pivotally connecting the other end of said supporting member to said switch blade, means for moving said supporting member and resilient connecting means between said supporting member and said switch blade for controlling the movement thereof.

7. A switch comprising a switch terminal, a blade for contacting said terminal, a supporting member for said blade, a link connecting said blade and said supporting mechanism for giving said blade a preliminary longitudinal movement when said supporting member is rotated, and a resilient connection between said switch blade and said supporting member for causing said switch blade and supporting member mechanism to operate in a unitary manner when the supporting member is rotated in the opposite direction.

8. A switch comprising a switch terminal, a blade for contacting said terminal, a supporting member for said blade, said supporting member being pivotally connected to said blade at one end, a link member pivotally connecting the other end of said supporting member to said blade, and a resilient connection between said supporting member and said blade for imparting a longitudinal movement to said switch blade when said supporting member is rotated.

9. A switch comprising a switch terminal, a blade for contacting said terminal, a supporting member for said blade, said supporting member being pivotally connected to said blade at one end, a link member pivotally connecting the other end of said supporting member to said blade, a resilient connection between said supporting member and said blade for imparting a longitudinal movement to said switch blade when said supporting member is rotated, a stopping member mounted upon said supporting member, and a resilient connection between said supporting member and said switch blade, said stopping member and said resilient means cooperating to place said supporting member and said link member in alignment after the preliminary longitudinal movement of said switch blade.

10. A switch comprising a switch terminal, a blade for contacting said terminal, a supporting member for said blade, said supporting member being pivotally connected to said blade at one end, a link member pivotally

connecting the other end of said supporting member to said blade, a resilient connection between said supporting member and said blade for imparting a longitudinal movement to said switch blade when said supporting member is rotated, a stopping member mounted upon said supporting member, and a resilient connection between said supporting member and said switch blade, said stopping member and said resilient means cooperating to place said supporting member and said link member in alignment during the rotation of said supporting member in a direction to cause said switch blade to contact said terminal.

11. A switch comprising a switch terminal, a blade for contacting said terminal, an insulating support for said terminal, a supporting member for said switch blade pivotally connected thereto at one end, a link member for connecting the other end of said support to said switch blade, an insulating rotatable support for said supporting member, said supporting member and said link member cooperating to give said switch blade a preliminary longitudinal movement when said supporting member is rotated.

12. A switch comprising a switch terminal, a blade for contacting said terminal, an insulating support for said terminal, a supporting member for said switch blade pivotally connected thereto at one end, a link member for connecting the other end of said support to said switch blade, an insulating rotatable support for said supporting member, said supporting member and said link member cooperating to give said switch blade a preliminary longitudinal movement when said supporting member is rotated, a spring connecting said supporting member and said switch blade adapted to bring the supporting member and link member into alignment with said switch blade after said preliminary longitudinal movement.

13. A switch comprising a switch terminal, a blade for contacting said terminal, a supporting member for said blade pivotally attached thereto at one end through a slot in said blade, a link member connecting the other end of said supporting member to said blade, means operative when said supporting member is rotated for imparting a preliminary longitudinal movement to said switch blade to cause said blade to move within said slot, and resilient means connecting said supporting member and said switch blade for maintaining said blade stationary in said slot during its further rotation.

14. In an electric switch, a supporting insulator, means for revolving the insulator about an axis other than the axis of the insulator, a switch member passing through the axis of revolution of the insulator and supported by the insulator, and an electrical connection with the switch member at the point

where the switch member intersects its axis of revolution.

15. In a switch, two links pivoted together at one end, a switch blade supported by the other end of both of said links, one of these supporting connections being a lost motion connection.

16. In a switch, an oscillatory supporting member, two links pivoted together at one end 10 and supported by said member, a switch blade, and connections between the other end of each of said links and said switch blade, one of said connections being a lost motion connection.

17. In a switch, a switch blade supported 15 to permit rotation and limited longitudinal movement, a link pivoted at one end to the switch blade, link means for revolving the other end of the link about the axis of rotation of the switch blade, and spring means for 20 moving the blade to its normal longitudinal position.

18. In a switch, a revolvable insulator, a switch blade supported by the insulator, a link pivotally connected to the switch blade, 25 the other end of the link being also revolvable about the axis of revolution of the insulator,

and spring means for urging the switch blade into its normal longitudinal position.

19. In a switch, an insulator revolvable about an external axis, a supporting base 30 fixed to the insulator, a switch blade pivoted to the base to swing with respect to the base about an axis coincident with the axis of revolution of the base.

20. In a switch, a revolvable insulator, a 35 supporting base fixed to the insulator, a switch blade pivoted to the base to rotate with respect to the base about an axis coincident with the axis of revolution of the base, and means for moving the switch blade with respect to its 40 axis of rotation.

21. In a switch, a fixed contact, a blade in engagement therewith, means for moving the blade out of engagement with the contact by successive longitudinal and rotating movements of the blade, said means being effective to rotate the blade in either direction from the contact to open the switch.

In witness whereof, we hereunto subscribe our names.

ALFRED ALSAKER.
SIDNEY J. LURIE.
